Henry P. Gale

By Wm. O. Bell Atty.

UNITED STATES PATENT OFFICE.

HENRY P. GALE, OF CHICAGO, ILLINOIS.

PAINTING APPARATUS.

Application filed November 2, 1925. Serial No. 66,137.

My invention relates to a novel and improved apparatus for use in applying paint to a surface in a spray. Various types of apparatus have been devised for this purpose, but they are all open to certain objections which I have overcome by my invention.

In one type paint is supplied to a spraying device commonly called a paint gun through a hose which is connected to a paint container, the paint being forced through the hose by means of air pressure. In this type slugs of paint form in the hose when it is not in use and then when it is again used these slugs are forced through the hose, provided sufficient pressure is present. If the hose has been completely clogged with slugs, as sometimes happens, to such an extent that it cannot be cleared by the ordinary pressure, then obviously something is bound to break and with disastrous results. In any case the gun is being moved over a surface and insufficient pressure is present to supply the proper amount of paint. This means that a comparatively bare spot is left on the surface which is difficult to refinish.

In another type of apparatus, it has been common to mount the paint gun upon a container provided with valves for regulating the flow of paint to the gun. These valves clog up with slugs in the same manner as the hose in the other type referred to and with much the same results. The can is usually blown off and before that occurs the quality of work is rendered poor because of the diminishing of the supply of paint. Of course, if the slugs are blown out, they become embedded in the finish on the surface to which the paint is being applied and detract from the appearance of the finished job as is well known.

Special containers have been provided with both of the above types of apparatus and because of their special and expensive construction, it has been customary to make an attempt to clean out a can when it is desired to change from one color of paint to another. This is effected by removing the entire cover which is clamped to the container and carries the valves and gauges commonly supplied with this equipment. In removing the cover either to clean the can or to refill the same paint is lost by leakage and spilling and moreover the valves in the top of the can become clogged with paint when the cans are shaken or tipped,

to which actions they are continuously exposed.

It is therefore the primary object of my invention to provide an apparatus in which clogging due to the formation of slugs shall be entirely avoided. This I achieve by mounting the paint gun directly upon the can of paint and providing a line of air hose to conduct air under a reduced pressure directly to the can, this pressure being controlled by a valve remote from the gun. In this manner it is not necessary for the paint to pass through any valves or hose, the paint being forced directly from the can to the gun. Very little, if any, paint can collect in the ordinary type of gun and moreover this instrument can be readily cleaned.

Another object of my invention is to provide a container of improved and inexpensive construction having means for attaching a spraying device or gun thereto and also having means for filling the same without removal of the gun. In present types of containers wherein the gun is mounted directly on a container, the gun is secured to the cover and in order to refill the container the entire cover is removed. Aside from the danger of spilling the paint which this construction involves the paint from the gun drips back through the connections and this paint is bound to be spilled on the floor or other support upon which the cover is placed. This objection is removed by my construction.

A further object of my invention is to provide a device which shall reduce the amount of air necessary to be used at the nozzle of the gun whereby excessive drying of the paint is avoided. In ordinary work and in the other types of apparatus referred to the amount of air supplied at the nozzle of a paint gun is so great as to dry the paint before it strikes the surface on which it is being sprayed. This prevents the proper amalgamation of the paint and causes streakiness and loss of color. These objections are overcome by my apparatus.

Further objects of my invention will become apparent during the reading of the following description in connection with the accompanying drawing wherein—

Fig. 1 is an elevation showing a general view of my improved apparatus.

Fig. 2 is a longitudinal section through my improved container and

Fig. 3 is a view partly in elevation and

partly in section and showing the construction of nozzle on a certain type of paint gun which I contemplate using with my invention.

- 5 Referring now to the drawings, the numeral 1 designates any suitable support upon which is mounted an air filter 2 to which air is supplied from any suitable source by means of the pipe 3. Air leaves the filter at 10 4 and passes through the reduction valve 5 to the T-connection 6 and thence to the pipe 7. Suitable gauges 8 and 9 are provided to indicate the pressure in the various pipes, as is well known in the art. The construction thus far described is old in the art and it is common to provide a suitable valve in the pipe 7 and to attach air hose thereto for use with one of the types of apparatus which I have referred to above.
- 15 20 I preferably extend the pipe 7, omitting the valve in its usual location and by means of the elbow 10 join the pipe 7 to another pipe 11 containing a suitable cut-off valve 12. The end of the pipe 11 is connected to 25 a hose 13, for a purpose which will presently appear.

The third leg of the T-connection 6 is connected to a pipe 14 containing a reducing valve 15, gauge 16 and cut-off valve 17 and 30 connected at its end to a hose 18 for a purpose which will presently appear.

Referring now particularly to Fig. 2, I have shown therein a container 19 provided with a threaded top edge 20 whereby a cover 35 21 may be secured to the container. The cover is provided with an opening 22 which is preferably located near the center of the can or container and which may have the upwardly extending flange 23 surrounding 40 the same and terminating in the downwardly extending flange 24 at the top of the flange 23. The opening is adapted to be closed by means of a cap 25, which is provided with an annular recess 26 in which is received a suitable packing 27 to contact with the top of the flange 23. The cap may be secured to 45 the cover by any suitable clamping means exemplified by a strap 28 adapted to span the cap and to have its ends received beneath the flange 24 and secured in position 50 by the screw 29. The cap is provided with an upwardly extending boss 30 through which extends a bore 31 connecting with a nipple 32 provided with suitable means to 55 secure thereon one end of the hose 18.

The cover 21 is further apertured at 33 to receive an outlet pipe 34 which extends into the container and nearly to the bottom thereof, the lower end being beveled, as shown at 60 35, to avoid the possibility of the pipe becoming clogged. The pipe may be secured in the cover in any suitable manner as by soldering to an upwardly extending flange 36 on the cover. The pipe extends above the 65 cover, as plainly shown, and at its upper end

is threaded to receive a union 37 by means of which it can be secured to a threaded stem 38 provided on a gun 39, a portion of which is shown in Fig. 3 and which is shown in Fig. 1 as secured in place upon the container.

The gun itself is of a type well known and forms no part of my invention. In Fig. 3 I have shown an enlarged view of a portion of this gun, the nozzle being shown in section so as to illustrate the construction thereof. Disposed within the nozzle 40 of the gun is a nozzle head 41 surrounding the tip 42. Paint is drawn through the tip 42 by means of air passing through the aperture 43 in the head and within which the tip is received. Ports 44 are provided in the head and disposed upon opposite sides of the tip 42 whereby when the paint leaves the tip, which it does in the form of a cone, the air from the ports 44 will impinge upon opposite sides thereof and flatten the cone out so that the paint will strike the surface to which it is to be applied in a wide strip, that is in the approximate shape in which a brush would apply the same.

The pressure of the air in the filter is usually about eighty pounds per square inch. This pressure is reduced by the reduction valve 5 to about seventy pounds per square inch and this is the pressure normally used to draw paint from the tip 42 and is also the pressure of the air passing through the ports 44 and impinging on the sides of the paint cone. The result is that the paint is dried too much by the air from the ports 44. This air not only completely atomizes the paint, which is desirable in itself, but it also dries it to such an extent that when it reaches the surface, which is normally about six inches from the nozzle, it is so dry that it will not properly amalgamate and will not have the necessary moisture to properly cling to the surface. It will also have lost its color to a large extent. The result is a job which is streaky and not uniform in color.

According to my invention I do not employ the pressure of air to suck the paint through the tip 42, but rely upon the pressure of air in the hose 18 and container 19. Because of the fact that this container is disposed closely adjacent to the gun it is possible to use a much lower pressure than where it is necessary to either force or suck the paint through a long line of hose. Therefore, I employ the reducing valve 15 to reduce the pressure to a very low point, varying from one quarter of a pound to three pounds per square inch. The result is that, while the pressure of air coming from the ports 44 is sufficient to flatten out the cone of paint, nevertheless it is not enough to dry the paint to an extent sufficient to cause the objections noted above.

From the above it will be apparent that I

have devised a painting apparatus of greatly improved character which will avoid the disadvantages due to the passage of paint through long lines of hose or through valves.

- 5 It will also be evident that I have devised a novel and improved container which may be readily filled without the necessity of removing the entire cover, thereby minimizing the danger of spilling paint due to either
 10 carelessness or leaking and which shall at the same time provide ready means for attachment of the paint gun and air line thereto. It is, of course, obvious that when the container is not in use in the apparatus suitable stoppers may be provided for the opening 22 and for the pipe 34. By my apparatus it will be evident that I have provided means making possible the reduction of the amount of air employed at the nozzles of a
 15 paint gun, which will result in an improved character of work as fully set forth above.

I am aware that changes in the form, construction and arrangement of parts may be made without departing from the spirit and 25 without sacrificing the advantages of the invention and I consider myself entitled to make all such changes as fairly fall within the scope of the following claims.

I claim:

- 30 1. In a painting apparatus, the combination of a pressure supply, a paint container, an atomizing gun, a valveless fluid outlet pipe rigid with the gun, said gun and pipe being mounted in the cover of the container 35 with the gun closely adjacent and directly upon the cover and the pipe extending down within the container close to the bottom thereof, a pressure conduit from the supply to the container, an independent pressure conduit from the supply to the gun, and in-

dependent means remote from the container and the gun for maintaining a greater degree of pressure in the gun than in the container.

2. In a painting apparatus, the combination of a pressure supply, a paint container, an atomizing gun, an outlet from the container to the gun, a pressure conduit from the supply to the gun, said container having a cover and said cover having a filling opening therein, a cap, means for detachably securing said cap to said cover to close said filling opening, said cap having a bore therein and a nipple connected with said bore, said gun being mounted upon said cover, a pressure conduit connected to the supply and to said nipple to admit pressure to the container, and independent means for maintaining the desired pressures in the container and gun. 45 50 55

3. In a painting apparatus the combination of a pressure supply, a paint container, a cover for said container having a filling opening therein, an atomizing gun, an outlet pipe rigid with the gun, said gun and pipe 60 being mounted in the cover of the container with the gun closely adjacent the cover and the pipe extending down within the container close to the bottom thereof, a pressure conduit from the supply to the gun, a cap for the filling opening in the cover and provided with a bore and a nipple connected with said bore, an independent pressure conduit from the supply to the nipple to admit pressure to the container, and independent means remote from the container and the gun for maintaining a greater degree of pressure in the gun than in the container. 65 70 75
